US00D568508S

(12) **United States Design Patent** (10) **Patent No.:** **US D568,508 S**
Howe et al. (45) **Date of Patent:** **** May 6, 2008**

(54) **TACTICAL FLASHLIGHT**

(75) Inventors: **Alan T. Howe**, Merrimack, NH (US);
Timothy R. Loring, Bedford, NH (US); **Christopher P. Levesque**,
Francesstown, NH (US); **Eric Yeates**, Virginia Beach, VA (US)

(73) Assignee: **Insight Technology, Inc.**, Londonderry, NH (US)

(**) Term: **14 Years**

(21) Appl. No.: **29/253,490**

(22) Filed: **Feb. 7, 2006**

(51) **LOC (8) Cl.** **26-02**

(52) **U.S. Cl.** **D26/38**

(58) **Field of Classification Search** D26/37,
D26/38, 40, 42, 46, 47, 50, 51, 52, 60, 130,
D26/132, 133, 136; 362/183, 157, 158, 190,

(57) **CLAIM**

The ornamental design for a tactical flashlight, as shown and described.

DESCRIPTION

FIG. 1 is a first perspective view of a second tactical flashlight of the present invention;

FIG. 2 is a second perspective view of the tactical flashlight of FIG. 1;

FIG. 3 is a front view of the tactical flashlight of FIG. 1;

FIG. 4 is a rear view of the tactical flashlight of FIG. 1;

FIG. 5 is a right side view of the tactical flashlight of FIG. 1;

FIG. 6 is a left side view of the tactical flashlight of FIG. 1;

FIG. 7 is a top view of the tactical flashlight of FIG. 1; and,

FIG. 8 is a bottom view of the tactical flashlight of FIG. 1.

1 Claim, 4 Drawing Sheets
